UNITED STATES PATENT OFFICE.

ALBERT H. GAESS, OF WATERBURY, CONNECTICUT, ASSIGNOR TO THE E. J. MANVILLE MACHINE COMPANY, A STATUTE CORPORATION OF CONNECTICUT.

PUNCH-TRANSFER MECHANISM FOR HEADING-MACHINES.

1,372,132.

Specification of Letters Patent. Patented Mar. 22, 1921.

Application filed January 13, 1920. Serial No. 351,217.

To all whom it may concern:

Be it known that I, ALBERT H. GAESS, citizen of the United States, residing at Waterbury, in the county of New Haven 5 and State of Connecticut, have invented a new and useful Improvement in Punch-Transfer Mechanism for Heading-Machines, of which the following is a specification.

10 In direct acting multiple-stroke metal heading machines wire or rod is fed into a die which is moved sidewise to cut off a blank and carry it into line with heading punches that are mounted in a holder attached to a vertically movable slide which is carried by a horizontally reciprocating gate. Between the reciprocations of the gate the slide is moved up and down so that the blank will first be acted upon by one 15 punch and then by another punch. An example of such a machine of the double acting type is illustrated and described in United States patent to A. C. Campbell, No. 926,170, June 29, 1909.

25 This invention relates to the mechanism which is provided in multiple-stroke heading machines for transferring the punches from position to position.

In these machines the punch slide is usually moved up and down at the proper intervals by means of cam operated levers and rockers, the throw of which is such that the motion of the slide is just equal to the distance between the centers of the punches, 35 the centers of which in striking position must exactly aline with the center of the die. A post and nut are ordinarily arranged on the gate to engage and stop the slide in its upward movement with the center of the lower punch exactly alined with the center of the die. A screw is commonly threaded in the slide so as to engage the gate and stop the slide in its downward movement with the center of the upper 40 punch exactly alined with the center of the die, and adjustable means are provided in the lever connections to enable the correct movement to be given to the slide between the stops.

50 If the operator on turning over the machine before starting the work, and particularly after changing the punches for different work or for some other reason, finds that a punch center is a few thousandths of an inch above or below the center of the

die or that the distance between the centers of the punches is not exactly the same as the throw of the operating mechanisms, he must reset the stops and readjust the lever and rocker connections to make the necessary 60 correction. With the machines as previously built it frequently happens that the operator attempts to correct the error by merely resetting the stops, as this appears to be the natural and easiest thing to do. As a result 65 of this, however, all of the parts between the cam and the stops are either stretched or compressed and the only thing accomplished is to produce distortion and excessive wear 70 on the parts. Furthermore, in the machines as now constructed, when operating at high speed the finished work is thrown promiscuously about the space between the die and gate and it sometimes happens that a blank 75 will become caught between the bottom of the frame or gateway and the top of a lever or rocker arm, with the result that the rocker is bent out of shape, or its key is sheared off, or the connection between the lever and rocker is broken, or the lever is 80 broken, or the cam shaft twisted, in any event the consequence being expensive damage.

The object of this invention is to so construct the punch transfer mechanism of machines of this class that no such damage will result from improper adjustment of the slide stops or lever connections, or from the accidental interposition of foreign pieces between moving parts of the transfer mechanism and adjacent fixed parts of the machine.

This object is attained by constructing the transfer lever, which is actuated positively and definitely by the cam, in such manner that while it has sufficient strength to perform its regular function it can yield on both the up and down strokes of the punch slide if the adjustments are imperfect or there is any interference with the normal 95 movements of the transfer mechanism.

In the accompanying drawings Figure 1 shows a general view of the punch transfer mechanism and its relative arrangement in a double-stroke header of the type shown in 105 the Campbell patent mentioned. Fig. 2 is a side elevation of the upper portion of the punch slide showing the adjustable stops. Fig. 3 is a rear elevation of the top of the slide and stops. Fig. 4 is, on larger scale, 110

an edge view of the cam lever with parts cut in section, as indicated by the line 4—4 on Fig. 5. Fig. 5 is a side elevation of the cam lever with portions in section. Fig. 6 shows, on still larger scale, a transverse section of the lever, as indicated by the line 6—6 on Fig. 5. Fig. 7 is a section on the line 7—7 on Fig. 5.

In the mechanism illustrated the punches 1 and 2 are mounted in a holder 3 that is secured to a slide 4 which is movable up and down in the front end of the horizontally reciprocating gate 5. At the lower end of the vertically movable slide is a plate 6 that is engaged and moved up and down at the proper time by the arms 7 of a rocker shaft 8. This rocker shaft has a rocker arm 9 that is adjustably connected with a lever 10 bearing rolls 11 which are engaged by a cam 12 on the cam shaft 13. The rotation of the cam through the lever and rocker raises and lowers the punch slide at the proper intervals to bring the punches alternately in line with the die. The adjustment to give the proper path of movement to the slide is made by changing the position of the sliding connecting block 14 by means of the screws 15 and 16. At the top of the slide is a rearwardly projecting bracket 17 which carries a stop screw 18 provided with a lock nut 19. A post 20 extends upward from the gate loosely through an opening in the bracket and is provided with a stop nut 21 and a lock nut 22 above the bracket. The screw 18 is set so as to engage the top of the gate and stop the downward movement of the slide when the center of the punch 1 is in line with the center of the die, and the nut 21 is set to engage the bracket and stop the slide in its upward movement with the center of the punch 2 in line with the center of the die.

As above stated, if adjustment is made by setting the stop screw or stop nut so that the punches will properly align with the die opening and no adjustment of the lever and rocker connection is made to correct the throw, all of the parts are put under strain and if not distorted and damaged are subjected to excessive wear. Furthermore, if a tool or piece of metal should by accident be laid upon the top of the gate in position to be engaged by the stop screw, or if a blank or other piece should get between the

bottom of the machine frame or gate and the operating parts, something must give way.

To eliminate these possibilities the cam lever 10 is made in two yieldingly connected sections—the section 23 with yoke 24 which encircles the operating cam and the section 25 with yoke 26 which holds the adjusting block. In the embodiment of the invention shown the adjacent ends of these cam lever sections are provided with two cylindrical pockets 27, and in

these pockets hollow cylinders 28 with one end closed are loosely fitted. In the cylinders are arranged headed plungers 29, and between the closed ends of the cylinders and the heads of the plungers are spiral compression springs 30. These springs are designed to thrust the cylinders in one direction and the plungers in the opposite direction, and the movements of the cylinders are limited by studs 31 that extend across the section 23 back of the closed ends of the cylinders and through slots 32 in the plungers, while the movements of the plungers are limited by studs 33 that extend across the section 25 in front of the heads of the plungers through slots 34 in the cylinders. With this arrangement the springs are always under compression and their resistance to compression is utilized in the normal operation of the mechanism and also in case of any misadjustment or accidental interference with the operation of the slide or connecting mechanisms. When the cam pushes the rear lever section forward the studs 31 push the cylinders forward and they in turn through the springs push the plungers forward and as the plungers engage the studs 33 the forward section of the lever is pushed forward. When the cam retracts the rear lever section the studs 31 draw back the plungers and they through the springs draw back the cylinders and these by engagement with the pins 33 draw back the forward section of the lever. If abnormal resistance is offered to the forward movement of the cam lever the springs are compressed and if abnormal resistance is offered to the retraction of the lever the springs are also compressed. Thus, by means of this mechanism, the possibility of damage resulting from the errors of adjustment or accidental interposition of pieces as previously mentioned is eliminated.

The invention claimed is:—

1. In a multiple-stroke heading machine the combination of a vertically reciprocating punch slide, means for raising and lowering said slide, a cam, a sectional yielding lever actuated by said cam, and an adjustable connection between said lever and said means for raising and lowering the slide, said lever being adapted to yield when resistance is offered to either the up or the down movement of the slide.

2. In a multiple-stroke heading machine the combination of a vertically reciprocating punch slide, a rocker for reciprocating the slide, adjustable stops for determining the limits of movement of the slide, a cam, a sectional lever actuated by said cam, an elastic connection between the sections of said lever, and an adjustable connection between said lever and said rocker.

3. In a multiple-stroke heading machine the combination of a vertically reciprocating

ing punch slide, means for raising and lowering said slide, adjustable stops for determining the limits of movement of the slide, a cam, and a sectional lever designed to yield when the slide reaches the limits of its movements actuated by said cam and connected with said means for raising and lowering said slide.

4. In a multiple-stroke heading machine the combination of a vertically reciprocating punch slide, means for raising and lowering said slide, a cam, and a sectional lever designed to yield on both the upward and downward movements of the slide actuated by said cam and connected with said means for raising and lowering the slide.

5. In a multiple-stroke heading machine the combination of a vertically reciprocating punch slide, means for raising and lowering said slide, a cam, and a sectional lever actuated by said cam and connected with said means for raising and lowering the slide, said lever sections being held together

against pull and thrust by means of springs under compression.

25

6. A transfer lever for multiple-stroke heading machines comprising two sections containing cylindrical pockets, cylinders loosely fitting said pockets, means limiting the movement of the cylinders in the pockets, plungers loosely fitting said cylinders, means limiting the movement of the plungers in the cylinders, and springs thrusting between the cylinders and plungers.

30

7. A transfer lever for multiple-stroke heading machines comprising two sections containing cylindrical pockets, cylinders loosely fitting said pockets, studs held by one lever section and passing through slots in the cylinders, plungers loosely fitting said cylinders, studs held by the other lever section and passing through slots in the plungers, and springs thrusting between the cylinders and the plungers and holding them extended against said studs.
